UNITED STATES PATENT OFFICE

2,165,854

AIR CONDITIONING APPARATUS

Billie Headrick, Wichita, Kans.

Application July 5, 1938, Serial No. 217,538

1 Claim. (Cl. 62—129)

The present invention relates to air conditioning apparatus designed primarily for use in cooling the air in the rooms of a building and has for its primary object to utilize water from a subterranean water supply to be pumped through a pair of cooling radiators and through which air is forced to lower the temperature thereof before feeding the same to the rooms.

A further object is to provide an apparatus of this character in which mechanical means is utilized to pump the water to the radiators and the discharge of the water from the radiators to the supply is utilized to decrease the pumping force required to supply the water to the radiators.

A further object is to provide an apparatus of this character of simple and practical construction, which is efficient and reliable in performance, relatively inexpensive to manufacture and maintain in operation and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which

Figure 1 is a side elevational view of the apparatus with parts shown in section.

Figure 2 is a sectional view taken substantially on a line 2—2 of Figure 1.

Figure 3 is a top plan view.

Figure 4 is a vertical sectional view through one of the radiators, and

Figure 5 is a sectional view of the pump.

Referring now to the drawings in detail, wherein for the purpose of illustration I have disclosed a preferred embodiment of the invention, the numeral 5 designates the basement floor 40 of a building beneath which is a subterranean water supply 6, the first floor of the building being designated at 7. A pair of well tubings 8 and 9 are sunk at spaced intervals through the floor 5 into the water supply 6 and within which pipes 10 and 11 respectively are positioned.

Mounted upon the floor 5 is a cooling chamber 12 having one wall provided with a screened opening 13 of sufficiently fine mesh to constitute a filter for air entering the chamber, the opposite end of the chamber being provided with an upstanding duct 14 leading through the floor 7, the discharge end of the duct being provided with a register 16.

Mounted in the chamber 12, adjacent the filter 13, is a cooling radiator 16 and a similar radiator

17 is mounted in the chamber adjacent the duct 14 as clearly shown in Figures 1 and 3 of the drawings. The radiators 16 and 17 are positioned in spaced relation and comprise upper and lower reservoirs 18 and 19 respectively connected by vertically extending spaced tubes 20, the upper reservoir 18 of the radiator 16 and the lower reservoir 19 of the radiator 17 are connected by an inclined pipe 21.

To the lower reservoir 19 of the radiator 16 is connected a supply pipe 22 leading to a centrifugal pump 23 shown in detail in Figure 5 and to one side of which is connected a supply pipe 26 connected to the feed pipe 10. The feed pipe 10 is also provided with a manually operable pump 27 and valves 28 and 29 are connected in the pipe 10 in advance of the pipe 26 and also in advance of the pump 27 as will be apparent from an inspection of Figure 1 of the drawings.

The pump 23 is operated by means of an electric motor 30 which also drives a pulley 31 over which a belt 32 is trained and arranged for operating a pulley 33 mounted in the chamber 12, said last named pulley driving a belt 34 trained over a pulley 35 on a shaft 36 supported in an elevated position above the floor 5 by brackets 37 arranged between the radiators 16 and 17.

A fan 38 is mounted on the shaft 36 for drawing air through the filter 13, through the radiator 16 and through the radiator 17 and forcing the same through the duct 14 into the room above the floor 7.

The top reservoir 18 of the radiator 17 has one end of the pipe 11 connected thereto, said pipe 35 also having a valve 39 interposed therein.

In the operation of the device the radiators 16 and 17 and the pipes leading thereto are supplied with water, preferably by means of the manually operated pump 27, after which the valve 29 is closed, the motor 30 started and water will continue to be forced through the radiators and discharged into the subterranean reservoir 6 through the pipe 11. At the same time, the fan 38 will be operated to draw air through the chamber 12 and where the same is cooled and discharged through the duct 14.

The discharge of the water from the radiator 16 into the radiator 17 and subsequently through the pipe 11 produces a siphoning action which facilitates the feeding of the water from the pipe 19 to the respective radiators and consequently reduces the load imposed upon the motor 30.

It is believed the details of construction and manner of operation of the device will be readily

understood from the foregoing without further detailed explanation.

Having thus described the invention, what I claim is:

- 5 An air conditioning apparatus comprising a closed water system including a water reservoir below the system, feed and discharge pipes extending upwardly therefrom, a chamber having an air discharge duct communicating with one 10 wall, an air intake in an opposite wall of the chamber having an air filter therein, a plurality of spaced apart radiators positioned in the chamber in the path of the air passing therethrough, an overflow pipe connecting the upper portion of 15 one radiator with the other radiator, said discharge duct being connected to the upper portion of the second named radiator, a pump connect-

ing the feed pipe with the lower portion of the first named radiator for drawing water from the reservoir and forcing the same through said radiator and returning the same to the reservoir, a fan operatively mounted in the chamber between the radiators for drawing air therethrough and discharging the same through said duct, a priming pump connected in a branch pipe of said feed pipe in advance of said first named pump, said overflow pipe preventing draining of the system backwardly from the second named radiator, a valve in the feed pipe in advance of both pumps to prevent draining of the water backwardly from the first named radiator, and a valve in the branch pipe leading to the priming pump. 15
